UNITED STATES PATENT OFFICE.

WILLIAM MONCRIEFF CARR, OF WOODCOURT, BROOKLANDS, AND THOMAS JAMES ASHLEY, DECEASED, LATE OF BROADSTAIRS, ENGLAND, BY ALICE ELIZABETH ASHLEY, EXECUTRIX, OF BROADSTAIRS, ENGLAND.

COAL-DISTILLATION APPARATUS.

Application filed February 25, 1926, Serial No. 90,714, and in Great Britain March 3, 1925.

This invention relates to apparatus for the distillation of coal and the production of coal gas in which the gas passes from a tier of retorts through branch connections into a stand-pipe where it is scrubbed and cooled on its way to a collecting or foul main, by a spray of liquid such as ammoniacal liquor projected into the stand-pipe. To provide for the proper control of the gas during the charging of the retorts it is usual to employ valves for closing the individual branch connections, and isolating discs or valves are provided for isolating the collecting or foul main from the stand-pipe when the retorts connected therewith are to be scurfed or placed under repair.

Now with the object of obtaining equal conditions of pressure on all retorts and with the object of obtaining an improved and more thorough washing and scrubbing action on the crude gas than has previously been possible in stand-pipes of uniform bore or cross-section it is proposed according to this invention to make use of a stand-pipe whose cross-sectional area increases progressively in the direction of the flow of the gases, either upwards or downwards the said increase being effected either by a series of set-offs or by a uniform tapering enlargement of the pipe. Where the crude gas is to be passed upwardly through the stand-pipe and washed and scrubbed by a descending stream of liquor, the cross-sectional area of the stand-pipe increases towards the top and that portion between the top retort and the collecting or foul main may be further enlarged and provided with a series of baffle plates arranged to project the liquor obliquely across the pipe in the form of films which the rising gases are obliged to penetrate. Owing to the increased cross sectional area of the stand-pipe at this point the velocity of the gas is considerably reduced, and more time is thus allowed for the liquor to take effect upon the gas.

It will also be seen that as the cross-sectional area of the stand-pipe at any given point is made substantially proportional to the quantity of gas to be carried the velocity of the gas will remain substantially constant throughout the length of the stand-pipe so that ample time is allowed for the liquor to effect its washing, scrubbing and cooling operations. Moreover, as the gas is kept in con-

tact with the liquor for a longer period, less liquor is required to effect the cooling. 55

The scrubbing and washing effect can be increased by increasing the height of the enlarged upper part of the stand-pipe as this effect is proportional to the size of the chamber so formed. It will be understood that 60 the provision for increased scrubbing and washing of the gas in the manner indicated will be of great advantage in works where the scrubbing and washing plant is limited in size or is of small capacity for the make of 65 gas.

A further advantage of this improved arrangement is found in that the successive offsets of the stand-pipe render possible the use of short connections between the retort 70 mouth-pieces and the stand-pipe and at the same time the retorts to be mounted in the setting in the most advantageous positions for heating.

This invention also provides (when conditions are favorable) for the sealing of the lower end of the stand-pipe by a water seal arranged at or above the level of the retort house floor, thus dispensing with the need for the usual "downtake pipe" extending to 80 sealing means beneath the floor, and also providing for immediate means of access to the bottom of the stand-pipe, for the purpose of cleaning it when necessary and without interference with the operation thereof. The 85 invention further provides means to prevent scrubbing liquor from entering the retort mouth-pieces through the branch connections, means to provide for the removal of particles of tarry matter adhering to the faces of the 90 valves which control the branch connections so as to enable the valves to be tightly closed, and finally an improved isolating disc or plate which can be moved quickly into position to isolate the stand-pipe from the collecting or foul gas main. 95

The invention is hereinafter more fully described with reference to the accompanying drawings wherein a preferred form of construction is illustrated. In these drawings:

Figure 1 is a front elevation of a portion of a retort bench showing a pair of stand-pipes of improved construction.

Figures 2 and 3 are respectively side eleva- 105
tion and plan views of the same.

Figure 4 is a front elevation partly in section showing a branch connection with the stand-pipe, the control valve and deflector means.

5 Figure 5 is a side elevation of the same with the valve removed.

Figure 6 is a sectional front elevation of the enlarged upper end of the stand-pipe containing baffles.

10 Figure 7 is a side elevation of a central baffle, and

Figure 8 is a side elevation of a side baffle.

Figures 9 and 10 are fragmentary side and front elevations respectively of a modified 15 arrangement wherein the enlarged upper part of the stand-pipe extends to a greater height and additional baffle means are provided.

On referring to these drawings it will be 20 seen that the stand-pipe *a* instead of being of uniform cross-section throughout as heretofore, is increased in cross-section from the bottom retort upwards by a series of set-offs *a'* thus providing an increasing bore or passage 25 for the rising gas so that the velocity of the gas is kept comparatively low to enable equal pressure to be maintained in all retorts and a thorough and effective washing and scrubbing action to be had within the 30 stand-pipe.

By this means much of the tar and other impurities in the crude gas are prevented from reaching the foul gas main. Moreover the scrubbing and cooling in the graduated 35 stand-pipe greatly relieve the other apparatus where complete purification of the gas takes place.

Each stand-pipe serves a tier of coal distillation retorts *b* and the retort mouth-pieces 40 are connected to the side of the stand-pipe by branch connections, preferably of the spherical jointed kind, described in British Patent No. 217,969, dated March 19, 1923. These branch connections *b'* as shown in Figure 4 are each fitted with a control valve *c* whereby the connection may be closed when the retort is being discharged and charged and an inclined deflector plate *d* is formed on or attached to the inner wall of the stand-pipe 50 at a point just above the control valve to prevent the descending liquor gaining access to the retort mouth, and at the same time serving to deflect a stream of liquor on to the face of the valve and keeping same clean.

55 The valve *c* is carried upon a lever arm *c'* seated on a shaft or spindle *c''* which passes through the wall of the stand-pipe, and is in the form of a plate of larger diameter than the annular seat with which it co-operates.

60 The valve is closed or opened by moving it towards or from the seat, this being effected by turning the shaft or spindle *c''* in one direction or the other. Particles of matter which adhere to these valves and seatings are

removed according to this invention by imparting a sliding motion to the valves. For this purpose the valve spindles *c''* may be provided with quick stitch-threaded screw or cam mechanism (not shown) for sliding the valves over their seats, or the spindles may as in the construction illustrated be so mounted that they can be slid endways by hand without the aid of any mechanical device, hand levers *c''* being provided on the outer ends of the spindles for their manipulation. 75

To facilitate the insertion and mounting of the valves, the stand-pipe is formed with apertures *e* adjacent the branch connections which apertures are normally closed by cover plates *e'* through which the valve operating 80 spindles project.

At a point above the uppermost of the retorts the stand-pipe is still further enlarged at *f*, and there contains a series of baffles adapted to project the descending liquor in the form of films obliquely across the path of the rising gas. As shown in Figures 6 to 8, this arrangement includes centrally disposed baffles *g* of inverted V-shaped construction and side baffles *g'* which are mounted on the inner sides of opposite walls of the stand-pipe in a manner permitting of their adjustment in a vertical direction. This enlarged portion of the stand-pipe may also be formed with apertures fitted with cover plates *f'* to facilitate access. In Fig. 1 the section line 1'-1' indicates the plane of the stage floor of the retort house. 85 90 95

At its upper extremity the stand-pipe *a* communicates by way of an inclined branch *h* with the collecting or foul gas main *i* and it is into this branch *h* that the ammoniacal liquor or other washing medium is projected, use being made for this purpose of a nozzle *j* which is preferably of the kind described 100 105 in said British patent.

To enable the stand-pipe to be isolated from the collecting or foul main *i* we propose to employ an apertured plate *k* which remains in position between two sections of piping in the branch *h*, the aperture in the plate registering under normal circumstances with the bore of the pipes. To isolate the stand-pipe the coupling bolts at the joint are slackened and the isolating plate is slid forward to move 110 115 a solid or non-apertured portion across the bore of the pipe.

At the bottom of the stand-pipe it is the usual practice to attach a "down take" pipe (which drains tar and liquor away from the stand-pipe) and to connect this pipe to a seal box situated below the floor. This pipe is liable to be obstructed and being difficult to clean is a source of trouble and delay. 120

We completely obviate this by dispensing 125 with the usual "down take" pipe entirely and we so arrange the bottom end of the stand-pipe that it makes a direct connection with a

seal box 1 placed at or about the level of the floor. This position greatly facilitates the inspection and cleaning of the seal box.

By connecting the seal pot to two stand-pipes and connecting the liquor overflow pipe to this it is possible to avoid obstruction of the regenerator flues.

In order to enhance the washing, scrubbing and cooling effects, the enlarged portion 10 at the top of the stand-pipe may be extended to a greater height and provided with additional baffles as shown in Figures 9 and 10. In this case the enlarged portion *f* continues 15 up as far as the inclined branch pipe *h* connecting with the collecting or foul main and the nozzle *j* for injecting the ammoniacal liquor or other washing medium is mounted centrally of the upper end of the enlarged 20 part of the stand-pipe. By this means the gas while travelling at a reduced velocity is subjected for a longer time to the influence of the washing medium and the washing, scrubbing and cooling actions are therefore effected to a greater degree.

25 It may in some cases be practicable to continue the enlarged portion of the stand-pipe right up to the foul main and to connect it thereto either directly or by a branch pipe of equivalent bore or cross-section.

30 We claim—

1. Apparatus for the distillation of coal and recovery of coal gas, comprising a stand-pipe having a series of enlargements whose cross-sectional area increases progressively 35 in the direction of the flow of the coal gas passing therethrough, a tier of retorts, branches connecting the stand-pipe with the mouths of the retorts, means for spraying liquor into the upper end of the stand-pipe, 40 and baffles for deflecting the descending stream of liquor from the branch connections.

2. Apparatus for the distillation of coal and recovery of coal gas, comprising a tier of

gas retorts, a stand pipe having a series of enlargements whose cross-sectional area increases progressively in the direction of the flow of the coal gas passing therethrough, 45 connections from the retorts to the said enlargements of the stand pipe, a further enlarged extension of the stand pipe above the 50 retorts, means for spraying liquid into the upper end of the extension, and baffles internally of said extension arranged to deflect the liquor obliquely across the pipe in the form of films across the path of the ascending gas. 55

3. Apparatus for the distillation of coal and recovery of coal gas, comprising a tier of gas retorts arranged out of vertical alignment, a stand pipe having a series of set-offs forming enlargements whose cross-sectional 60 area increases progressively in an upward direction, short connections of uniform length between the retorts and the stand pipe, means for spraying liquid into the upper end of the stand pipe, a gas collecting main, and pipe 65 sections connecting the upper end of the stand pipe therewith.

4. Apparatus for the distillation of coal and recovery of coal gas, comprising a tier of gas retorts, a stand-pipe extending upwardly 70 adjacent the retorts and having a series of set-offs forming enlargements whose cross-sectional area increases in an upward direction, connections from the retorts to the stand pipe, means for spraying liquid into the upper end of the stand pipe, a pipe section connecting the upper end of the stand pipe with a gas collecting main, an isolating plate in 75 said pipe section, and a seal box directly connected with the lower end of said stand pipe. 80

In testimony whereof they have affixed their signatures.
